UNITED STATES PATENT OFFICE.

JAMES O. ATKINS, OF LONG ISLAND, KANSAS.

DESIGN FOR A REIN-SUPPORT.

SPECIFICATION forming part of Design No. 31,643, dated October 10, 1899.

Application filed August 17, 1899. Serial No. 727,589. Term of patent 7 years.

To all whom it may concern:

Be it known that I, JAMES O. ATKINS, a citizen of the United States, residing at Long Island, in the county of Phillips and State of Kansas, have invented and produced a certain new and original Design for Rein-Supports; and I do declare the following to be a full, clear, and exact description of the invention, such as will enable others skilled in the art to which it appertains to make and use the same.

The invention has relation to a new and original design for a rein-support; and it consists of a rein-support of the configuration shown in the accompanying drawing, in which I have illustrated my invention in perspective.

The leading feature of the design comprises a rod 1, the upper end of which is provided with a laterally-disposed bail 2, having upwardly-projecting ends 3 spaced apart. Below the bail is a hook 4, the free end of which projects upwardly.

What I claim is—

The design for a rein-support as herein shown and described.

In testimony whereof I have hereunto set my hand in the presence of two subscribing witnesses.

JAMES O. ATKINS.

Witnesses:

E. M. WEED,
J. M. FIGLEY.
